ATTORNEY

UNITED STATES PATENT OFFICE.

JOHN HAWLOWETZ, OF NEW YORK, N. Y.

MACHINE FOR DRYING FEATHERS.

SPECIFICATION forming part of Letters Patent No. 259,388, dated June 13, 1882.

Application filed April 21, 1882. (No model.)

To all whom it may concern:

Be it known that I, JOHN HAWLOWETZ, of the city, county, and State of New York, have invented certain new and useful Improvements 5 in Machines for Drying Feathers, of which the following is a specification.

Ostrich and other feathers, which are used to a great extent for the trimming of ladies' hats, require to be carefully cleaned by washing, after which they are sized and dried, and then dyed or otherwise prepared and finished for use. The drying operation was heretofore accomplished by hand by taking hold of the feathers with the right hand and expelling the 15 adhering water and size by striking a few blows on the left arm, whereby the surplus size is removed and the vanes of the feathers spread, the feathers being then completely dried by being hung up in a hot room.

20 The object of this invention is to substitute for the hand-labor heretofore required an improved machine, whereby the drying of a large number of feathers may be accomplished in a quicker and more perfect manner; and the invention 25 consists of a closed drying-chamber, which is provided at its interior with fixed inclined transverse wire frames or gratings that are arranged at both sides of oscillating beater-frames, to the opposite ends of which the wet 30 and sized feathers are applied, so that by the oscillations of the beater-frames the feathers are struck against the inclined wire frames, and thereby the moisture and surplus size removed.

In the accompanying drawings, Figure 1 35 represents a vertical longitudinal section of my improved apparatus for drying ostrich and other feathers. Fig. 2 is a longitudinal section of the same on line $\alpha\alpha$, Fig. 1, and Figs. 3 and 4 are respectively a detail top view and 40 a section of that portion of the beater-frame which holds the feathers in beating.

Similar letters of reference indicate corresponding parts.

The ostrich or other feathers are applied, after being cleaned and sized in the usual manner, by their quills to the opposite ends of the oscillating beater-frames A, which are arranged at the interior of a closed drying-chamber, B, the center shafts of the beater-frames 45 50 A turning in suitable bearings in the side walls of the drying-chamber B. The end walls of

the drying-chamber B are arranged with hinged doors having glass windows, so as to give access to the interior of the frames and admit of the progress of the drying process to be 55 observed from the outside.

The oscillating motion is imparted to the beater-frames A, either by hand or power, the shafts of the frames being for this purpose extended to one end through the side wall of the 60 drying-chamber B, and provided with cranks which are connected by a crank-rod to an eccentric of a driving-shaft, supported in bearings at the top of the drying-chamber. The beater-frames A are arranged at their opposite 65 ends with a number of transversely-stretched retaining-wires, $a a$, through which the quills of the feathers are alternately passed, as shown in Figs. 3 and 4.

The thickest ends of the quills are furthermore secured by means of twisted binding-strings and fastening-wires b to side hooks b' of the beater-frames A. By the pressure of the stretched transverse wires and the retaining action of the twisted binding-strings the 75 feathers are securely held parallel to each other at both ends of the beater-frames, so that by the oscillations of the same they are brought with considerable force into contact with fixed inclined wire frames or gratings C at the in- 80terior of the chamber B.

Two wire frames C are arranged at each end of a beater-frame—one above the other below the same—at such angles of inclination as correspond to the terminal positions of the os- 85 cillating beater-frames. Each beater-frame A works consequently in connection with four fixed wire frames C, so that the feathers are thrown at each oscillation against two wire frames located diagonally to the shaft of the 90 beater-frame.

To soften the blow of the beater-frames upon the fixed wire frames C, one of each pair of beater-frames is provided with rubber cushions d , as shown in Figs. 1 and 2.

The interior of the drying-chamber is heated by steam or otherwise, and the surplus moisture drawn off to the exterior by means of a suction-fan or other ventilating device operated by a belt and pulley in connection with the driving-shaft of the beater-frames, as shown in Fig. 1.

In this manner a large number of feathers may be quickly freed of the adhering size and moisture by the beating action of the oscillating frames upon the fixed wire frames, and then dried by exposure to the high temperature kept up in the interior of the drying-chamber.

The feathers are thus dried in a more uniform manner and at less cost than by hand-labor, without exposing the workmen to the high temperature in which they are now required to work in order to properly heat up and dry the feathers.

Having thus described my invention, I claim as new and desire to secure by Letters Patent—

- 15 1. An apparatus for drying ostrich and other feathers, consisting of a tightly-closed drying-chamber, fixed interior wire frames arranged at a suitable angle of inclination, and of intermediate oscillating beater-frames provided with means to attach the feathers to their opposite ends, substantially as set forth.
- 20

2. The combination of a closed drying-chamber having fixed interior wire frames, the latter being provided with rubber cushions, with oscillating beater-frames having means to attach the feathers to their opposite ends, substantially as set forth.

25 3. In an apparatus for drying ostrich and other feathers, a beater-frame, A, having transverse retaining-wires *aa* at opposite ends, and transverse binding-strings *b*, applied to the frame back of the retaining-wires, substantially as described.

30 In testimony that I claim the foregoing as my invention I have signed my name in presence of two subscribing witnesses.

JOHN HAWLOWETZ.
